SAFETY RAZOR

Meyer J. Shnitzler, Brookline, and Frank Ferrara, Medford, Mass., assignors to The Gillette Company, Boston, Mass., a corporation of Delaware.

Application April 24, 1952, Serial No. 284,114

10 Claims. (Cl. 30—60.5)

This invention comprises a new and improved safety razor of the unitary type, that is to say, of the type that has no loose or detachable parts. Such safety razors include a spider movable with respect to the blade seat and carrying pivotally mounted cap sections. The opposite ends of this movable spider have heretofore been more or less exposed, and it has sometimes resulted that the user will hold the razor between his thumb and forefinger by the ends of the spider and so interfere with the free closing movement of the razor, perhaps by displacing the blade from the blade seat so that it is caught by the closing cap sections. This is particularly likely to occur when the user is changing from the use of a three-piece razor and has thus acquired the habit of holding the razor head by its ends with one hand and turning the handle with his other hand in clamping or releasing the blade. Danger of cutting is avoided in handling razors of that type by holding the razor head in this manner and contacting the unsharpened ends of the blades at the ends of the razor head rather than attempting to engage the sides of the razor where the sharp blade edges are partially exposed.

An important advantage of the improved razor of the present invention is that both ends of the spider are completely shielded by stationary protectors which also serve as convenient finger grips for holding the razor while a fresh blade is being presented thereto or a used blade removed therefrom. In the razor of the present invention the movement of the ends of the spider in closing the cap sections takes place in a path that is completely enclosed by extensions from a relatively stationary portion of the razor that may take the shape of wide flat aprons, not only covering the moving parts, but presenting extended finger grips that are comfortable to the hand of the user and located where they will be most naturally engaged.

The aprons which serve as shields and finger grips have also a third function in that they reinforce and support the points of connection between the spider and the cap sections. Thus, these parts which are preferably of somewhat delicate construction, are reinforced and held positively against springing even when an undue amount of force is exerted by the user in clamping the blade for shaving.

Many advantages of the improved razor reside in constructional features that permit it to be constructed of prefabricated steel parts in an economical manner and facilitate the employment of fixtures for assembly in manufacture. The construction is also such that in a finished razor, plating protects all points of connection between the various parts of the razor and so obviates corrosion and insures long life in use.

These and other features of the invention will be best understood and appreciated from the following description of a preferred embodiment thereof selected for purposes of illustration and shown in the accompanying drawings in which:

Fig. 1 is a view in perspective of the razor in closed position and on an intermediate enlarged scale.

2

Fig. 2 is a view of the razor head in longitudinal section. Fig. 3 is a view in perspective of the parts of the spider. Fig. 4 is a view in perspective of the guard or blade seat member, and

5 Fig. 5 is a fragmentary view showing one end of the razor head with the shell or finger grip broken away.

The various parts of the razor, except its handle, are so designed that they may be prefabricated from sheet steel by simple stamping and bending operations. The 10 guard or blade seat member as best shown in Fig. 4 is formed of sheet metal of uniform thickness. It comprises an approximately rectangular blade seat 10 having embossed or molded therein an elongated diamond-shaped depression 11 and provided in each end with a T-shaped aperture 12 which extends partly into the depression 11 and which is designed to permit the free vertical passage of one arm of the spider as will presently be described. The longitudinal edges of the blade seat member are turned downwardly to provide rounded 15 guard flanges 13. These may be transversely scored as shown and partially set off from the body of the blade seat member by elongated narrow slots.

The end portions of the member 10 merge into necks 14 of reduced width and these necks in turn merge through 20 a rounded bend into down-turned integral aprons 15 that are substantially wider than the necks 14 and as herein shown extend transversely and outwardly slightly beyond the ends of the guard flanges 13. As optional features, each of the aprons 15 is shown as having its outer surface 25 scored and as being provided with an inwardly depressed area 16 which provides an inwardly offset surface. The reduced neck 14 is defined by symmetrically disposed square notches 17 in the member 10 and these, as it will be seen, provide passages for the arms of the cap sections. The blade seat member 10 is further provided with a centrally disposed hole 18 located in the bottom of its diamond-shaped depression 11 and permitting passage 30 of a stem for connection with the handle of the razor.

The spider comprises a two-ply longitudinal bar 20 35 provided with a centrally located down-turned stem 21. The bar merges at both ends into flat down-turned arms 22, the bar being undercut at each end so that hooked projections are provided either of which may be engaged 40 with the slot of a longitudinally slotted blade when it is desired to supply such a blade from a blade dispensing magazine. Each of the down-turned arms 22 is provided at its lower end with a square outwardly projecting boss 23 and upon each of these bosses is mounted a cross 45 bar 24 having a centrally disposed square aperture shaped to fit the boss 23. The bosses 23 terminate flush with the outer surface of the bars 24 but do not pass through them. Each of the bars 24 has a wide central section in which the aperture is formed and oppositely 50 extending arms of reduced width and each of these terminates in an outwardly turned ear constituting a pivot 25. As already observed, it will be seen that the parts of the spider above-described may be formed by shearing from sheet metal of uniform thickness, supplemented or preceded in the case of the cross bar 24 by a folding operation to provide the two-ply structure and a swaging operation to form the pivots 25.

The cap sections 27 collectively form a substantially 55 rectangular blade-clamping member overlying the blade seat 10, and are notched in their meeting edges to provide clearance for the longitudinal bar 20 of the spider. Each cap section 27 is provided at its opposite corners with a flat down-turned arm 28, perforated at its lower 60 end to receive one of the pivots 25 which projects outwardly from the ends of the cross bars 24 of the spider. Each of the arms 28 terminates in an outwardly extending 65 in ear 29 which is so located as to encounter one end of the guard flange 13 when the spider is moved upwardly.

Fig. 1 is a view in perspective of the razor in closed position and on an intermediate enlarged scale.

When this occurs, the pivots 25 pass above the ends of the guard flanges 13 and the engagement of the ears 29 with the ends of the flanges 13 causes the cap sections to swing outwardly and fully to expose the blade seat 10. The arms 28 of the cap sections slide upon the outer surface of the cross bars 24 and thus prevent them from becoming disengaged from the bosses 23.

The razor includes a handle 30 in the end of which is inserted a tubular metal plug 31 passed through the hole 18 of the blade seat member and spun outwardly into a flange 32, thus rotatively connecting the handle with the blade seat member. The stem 21 of the spider is provided with a threaded extension 33 which is received in a correspondingly threaded socket in the plug 31. Accordingly, by rotating the handle, the spider is moved relatively up and down with respect to the blade seat, and the cap sections are correspondingly opened or closed. In these operations the razor head may be conveniently held between the thumb and forefinger of the user through the medium of the aprons 15, and these aprons completely shield the opposite ends of the spider, including the cross bars 24 and also the down-turned arms of the cap sections. The opening and closing of the cap sections and the position of the blade upon the blade seat are, therefore, completely shielded from interference.

It will be noted from an inspection of Fig. 2 that the inner surfaces of the aprons, namely the inner faces on either side of the depressed areas 16 lie flush with the outer faces of the arms 28, so that the points of connection of these arms and the pivots 25 slide in engagement with the inner faces of the aprons and thus are securely backed up and reinforced by the aprons both when the spider occupies its lower or blade-clamping position and while in transit from one position to the other. Therefore, in the event of excessive pressure in clamping the razor parts, outward deflection of the arms 28, which might otherwise occur, is positively prevented.

It will be noted that the blade 40 projects at its unsharpened end edges slightly beyond the reduced necks 14 of the blade-seat member and that the rounded bend of these necks in merging into the aprons 15 provides space into which the flesh of the user's thumb and forefinger may slightly bulge in grasping the ends of the blade. This not only facilitates removal of a used blade, but enables the user to follow the same technique he may have practised in using a three-piece razor, that is to say, he may hold the razor head by the grips afforded by the aprons 15 in one hand after he has presented a fresh blade and turn the handle 30 with the other, all without altering his grasp on any part of the razor. And he may grasp the unsharpened ends of the blade without changing the position of his hand on the finger grips.

It has been pointed out that the aprons 15 back up and reinforce the points of pivotal connection between the bars 24 and the arms 28 of the cap sections. The inwardly offset areas 16 correspondingly back up and reinforce the point of connection between each of the bars 24 and the down-turned arms 22 of the spider by engaging the bars in areas about the ends of the boss 23.

The aprons have still another useful safety function and that is they reduce the drop damage to the razor by covering the more delicate articulated parts of its structure.

Having thus disclosed our invention and described in detail an illustrative embodiment thereof, we claim as new and desire to secure by Letters Patent:

1. A safety razor comprising a guard member having a blade seat, a spider movable with respect to said seat and including a downwardly extending arm at each end having an outwardly projecting lug, a cross bar carried by each of said lugs, and cap sections pivotally connected to said cross bars and having downwardly projecting por-

tions arranged to swing over the outer faces of the cross bars.

2. A safety razor comprising a guard member having a blade seat, a spider movable with respect to said seat and including a downwardly extending arm at each end having an outwardly extending lug, a cross bar fitted at an intermediate point on each lug and having an outwardly directed pivot at each end, and cap sections having downwardly extending arms connected to said pivots and holding the cross bars from disengagement with the said lugs.

3. A safety razor comprising a blade-supporting member and a pair of overlying cap sections having integral down-turned end portions spaced to embrace the ends of said blade-supporting member, a spider movably mounted in said member, separate cross bars mounted on bosses at opposite ends of the spider and held against removal by the down-turned end portions of the cap sections, and pivotal connections between the cap sections and said cross bars.

4. A safety razor comprising a guard member having a blade seat with a longitudinal slot therein, a spider having a longitudinal bar movable through said slot and downturned arms at both ends extending below the guard member, a separate cross bar suspended at its center upon each of said arms, cap sections shaped to overlie the guard member and having downturned arms pivotally connected to the outer ends of the said cross bars, and fixed aprons holding each suspended cross bar in place by engaging it about its point of suspension.

5. A safety razor comprising a blade-seat member of sheet metal having its outer ends downturned at right angles and extended transversely, a spider movable with respect to said member and having down-turned arms presenting outwardly directed pivots, and cap sections mounted on said pivots and supported at their points of pivotal connection by sliding contact with the inner surfaces of the down-turned ends of the blade-seat member.

6. A safety razor comprising a blade-seat member of sheet metal having down-turned finger grips of substantial area at both ends, a spider movable with respect to said member, and cap sections pivotally connected to, and outwardly of, the spider and positioned within said finger grips and confined against outward displacement by movable contact with said finger grips.

7. A safety razor comprising a blade-seat member, a handle having a rotary connection with said member, a spider having a threaded connection with the handle, cap sections pivotally mounted outwardly on the ends of the spider, and sheet metal aprons of substantial area formed integrally with the blade-seat member and spaced to span the points of pivotal connection when the cap sections occupy their blade clamping position in cooperation with the blade-seat member and to make sliding engagement with said points in the movement of the cap sections to their open position.

8. A unitary safety razor having a head portion including a guard member presenting a blade seat, a spider having separate cross bars suspended at each end, cap sections pivotally connected to said cross bars, a handle rotatably connected to the guard member and having a threaded connection with the spider, and finger grips in the form of wide sheet metal aprons connected to the guard member and extending transversely across the ends of the head portion in sliding engagement with said cross bars, thus leaving the latter free for movement when the handle is rotated in opening or closing the razor.

9. A safety razor comprising a guard member, a spider, cap sections having arms pivoted to the spider outwardly thereof, and downturned aprons at each end of the guard member each having an inner surface disposed in sliding engagement with the points of pivotal connection

between the cap sections and the spider to back up and reinforce the same.

10. A safety razor comprising a guard member having a blade seat, a spider having separate cross bars suspended at each end thereof, cap sections shaped to overlie the guard member and having downturned arms pivotally connected to the outer ends of the said cross bars, and downturned aprons at each end of the guard member, each apron having inner surfaces disposed in sliding engagement with the points of pivotal connection between the cap sections and the spider and further each

having an inwardly offset area holding each suspended cross bar in place by engaging it about its point of suspension.
